UNITED STATES PATENT OFFICE.

JULIUS W. FORSE, OF BISHOP HILL, ILLINOIS.

RAIL-JOINT.

1,157,770.

Specification of Letters Patent.

Patented Oct. 26, 1915.

Application filed July 31, 1915. Serial No. 42,974.

To all whom it may concern:

Be it known that I, JULIUS W. FORSE, a citizen of the United States, residing at Bishop Hill, in the county of Henry and State of Illinois, have invented certain new and useful Improvements in Rail-Joints, of which the following is a specification, reference being had to the accompanying drawings.

10 This invention relates to certain improvements in rail joints and it is an object of the invention to provide a joint of the general character having novel and improved means whereby the tread surfaces are maintained substantially flush whereby the possibility of "pounding" is substantially eliminated.

Furthermore, it is an object of the invention to provide a novel and improved rail joint wherein the same possesses maximum strength and whereby the weight is equally distributed upon the meeting ends.

20 The invention consists in the details of construction and in the combination and arrangement of the several parts of my improved rail joint whereby certain important advantages are attained and the device is rendered simpler, less expensive and otherwise more convenient and advantageous for 25 use, all as will be hereinafter more fully set forth.

The novel features of the invention will be carefully defined in the appended claims.

In order that my invention may be the 35 better understood, I will now proceed to describe the same with reference to the accompanying drawings, wherein—

Figure 1 is a view in perspective illustrating a rail joint constructed in accordance with an embodiment of my invention; Fig. 2 is a vertical sectional view taken through the device as disclosed in Fig. 1, an end of a rail being shown in elevation together with the key herein employed; and 45 Fig. 3 is an enlarged view in perspective of the block, detached as herein embodied.

As disclosed in the accompanying drawings, 1—1 denote the meeting ends of rails having their web portions 2 thickened, said 50 thickened portions 2 having their outer surfaces flush with the marginal portions of the tread 3 and the flanges 4 of the rails. Each of the rails has produced longitudinally thereof and substantially midway of 55 its height the open end slot 5 terminating

in the vertically disposed elongated openings 6, the communication of the slot with the opening being at substantially the longitudinal center of the opening.

7 denotes a block of the same width as 60 the meeting ends of the rails and adapted to be inserted within the aligned slots 5, and the opposite ends of said block are provided with the heads 8 adapted to be snugly received within the openings 6. By this arrangement it will be perceived that the 65 meeting ends of the rails are effectively connected and that the weight is evenly distributed. Furthermore, it is to be observed that the block 7 serves to maintain the tread 70 surfaces of the rails flush so that the possibility of "pounding" is eliminated.

In order to maintain the block 7 against displacement, I provide the top and bottom of the meeting ends of the rails 1 with the 75 vertically disposed channels 9 affording an opening through which is directed the key 10, said key being also disposed through an opening 11 formed in the block 7 at substantially the center thereof. It is preferred that said key be substantially flat 80 and that the upper extremities of the channels 9 be enlarged so that the upper extremity of the key may be maintained below the tread surfaces of the rails 1 and be free 85 of contact with the wheels of the rolling stock passing thereon.

From the foregoing description, it is thought to be obvious that a rail joint constructed in accordance with my invention is 90 of an extremely simple and comparatively inexpensive nature and is particularly well adapted for use by reason of the convenience and facility with which it may be assembled, and it will also be obvious that 95 my invention is susceptible of some change and modification without material departure from the principles and spirit thereof and for this reason I do not wish to be understood as limiting myself to the precise arrangement and formation of the several parts herein shown in carrying out my invention in practice.

What I claim is:

1. A rail joint comprising the meeting 105 ends of rails having open end slots produced in the opposed end faces thereof, the inner ends of said slots being enlarged, a block insertible within said slots when the rails are assembled, and a vertically dis- 110

posed key directed through the meeting ends of the rails and the block for maintaining the block against displacement.

2. A rail joint comprising the meeting ends of rails having open end slots produced in the opposed end faces thereof, the inner ends of said slots being enlarged, a block insertible within said slots when the rails are assembled, the opposed faces of the meeting ends of the rails being provided with vertically disposed channels to form an opening, the block being provided

with an opening to register with the opening afforded by the channels of the rails, and a key insertible through said openings 15 for maintaining the block against displacement.

In testimony whereof I hereunto affix my signature in the presence of two witnesses.

JULIUS W. FORSE.

Witnesses:

LEROY F. ERICSON,
A. E. ANDERSON.
